UNITED STATES PATENT OFFICE.

LOUIS N. VINCENT, OF SEATTLE, WASHINGTON; JESSIE R. VINCENT, EXECUTRIX OF SAID LOUIS N. VINCENT, DECEASED, ASSIGNEE TO IMPERIAL STEAM APPLIANCE COMPANY, OF SEATTLE, WASHINGTON, A CORPORATION.

FLANGE LUBRICATOR.

Application filed December 5, 1922. Serial No. 604,992.

My invention relates to improvements in flange lubricators for wheels, and more particularly to lubricators for use in lubricating the flanges of the wheels of locomotives, steam, electric and other cars, etc.

My invention consists in the several features, and in the construction, combination and arrangement of such features as more fully hereinafter described and claimed.

10 The object of the invention is to thoroughly and constantly lubricate the flanges of the wheels of a locomotive or car, especially when the wheels are travelling on the curved portions of a track, as very little, 15 if any, lubrication of the flanges is necessary when the wheels are travelling on a straight track.

A further object is to dispense with the use, as a lubricant, of solid stick grease, and 20 thick grease of all characters which have many disadvantages, and substitute oil therefor as a lubricant.

25 A further object is to provide a flange lubricator for wheels which will cause the oil or lubricant to be automatically fed to the flanges of the wheels by means of the lateral or sidewise movement or play of the truck or engine frame and also the lateral movement of the wheels between the rails 30 during their travel on the track.

35 A further object is to provide a flange lubricator for wheels which will operate continuously and automatically and require no attention or care except the keeping of the lubricant receptacle constantly supplied with oil or lubricant.

40 A further object is to provide a flange lubricator for wheels having a wick or brush with means for keeping the same constantly and evenly pressed against the flange of the wheel and also means for constantly supplying the brush with oil.

45 A further object is to provide a flange lubricator which will entirely eliminate the possibility of the oil or lubricant being spread onto the tread of the wheel, and which is mounted in such manner that when the flange of the wheel comes in contact with the lubricator it does not cause an excessive amount of oil to be spread on the flange of the wheel.

50 A still further object is to provide a flange lubricator for wheels which is simple, inexpensive and durable in construction, oc-

cupies a minimum amount of space, requires 55 no adjustment of parts after being installed, the several parts not being liable to get out of order even with hard usage, and which operates easily and silently, thereby obtaining a maximum effectiveness.

60 The invention consists in the several features and in the construction, combination and arrangement of such features as more fully hereinafter described and claimed.

65 Referring to the drawings:—
Fig. 1 is a side view in elevation of my invention.

70 Fig. 2 is a central longitudinal section.
Fig. 3 is a vertical section taken on the line 2—2 of Figure 1.

75 Fig. 4 is a detail section of the sleeve.
Fig. 5 is a detail section of the plunger.

In the drawings, in which similar reference characters denote similar parts throughout the several views, 1 represents 75 the flange lubricator, in which oil is to be used as the lubricant instead of grease, 2 the oil receptacle or container which is mounted at the top of a vertical pipe 3 and is provided with a closure 4.

80 A horizontal casing 5 is provided, having an upwardly extending interiorly screw-threaded projection 6 in which the lower end 7 of the pipe 3 is screwed, 8 being a series of oil inlet or strainer openings in 85 the bottom of the projection 6, through which oil is fed to an interior chamber 9 of the casing 5.

85 The outer end 10 of the casing 5 is provided with interior screwthreads 11, and a 90 barrel or sleeve 12 is mounted in the chamber 9 and is provided with a head 13, having screwthreads 14, which engage the screwthreads 11 and hold the barrel in place. The barrel 12 is reduced in diameter from 95 a point 15 at the rear of the head 13 to the extreme end 16 thereof and adjacent such end a pin 17 is mounted. Telescopically mounted to slide freely in the barrel 12 is a 100 hollow plunger 18, which is provided with upper and lower longitudinal slots 19 and 20, respectively, through which the pin 17 passes and through which the oil enters the interior of the hollow plunger from the container 2, through pipe 7 and through the 105 series of inlet openings 8.

The inner end of the plunger 18 is provided with an enlarged head 21 having a

suitable packing ring 22 in order to provide a tight joint between the interior chamber 9 of the casing 5 and the head 21 of the plunger 18.

Just beyond the head 21 the plunger is provided with an exteriorly screwthreaded projection 23, and 24 is a wick or brush engaging the screwthreaded projection 23, and 25 is a sleeve or casing slidably mounted 10 in an aperture 26 in the inner end of the casing 5, which surrounds and encloses the wick or brush 24, its inner end abutting against the head 21 and its outer end being inclined or formed at an oblique angle as 15 at 21^a in order to conform to the inclination of the flange of the wheel.

In order to retain the brush in constant contact with the flange of the wheel a helical spring 27 is provided located in the interior 20 of the barrel 12, intermediate the head 13 of the barrel and the outer end 28 of the hollow plunger 18.

In operation, the oil flows from the oil container 2 down the pipe 3, through the 25 series of inlet openings and strainers 8 until it fills the chamber 9 of the casing 5, flows through the slots 19 and 20 of the plunger and fills the interior of the same and also the barrel 12, and the outer end 21^a of the 30 sleeve 25 and the wick or brush 24 continually contacting and bearing tightly against the flange of the wheel, the force of the contact being regulated by the strength or tension of the helical spring 27. When the lateral sidewise movement or play of the wheel or wheels causes the sleeve 25 and barrel 12 to be pushed or moved inward, against the pressure or tension of the helical spring 27, the oil contained in the chamber 9 is 40 forced through the slots 19 and 20 into the interior of the hollow plunger 18, by the pressure on the oil of the head 21 of the plunger, and the oil is forced by such pressure from the hollow plunger into and 45 lengthwise through the bristles of the brush, or the wick from end to end which spreads the oil evenly on the flange of the wheel.

I do not wish to be understood as limiting myself to the specific details of construction and arrangement as herein described and illustrated, as it is manifest that variations and modifications may be made in such features of construction and arrangement, in the adaptation of the device to the various 55 conditions of use, without departing from the spirit and scope of my invention and improvements. I, therefore, reserve the right to all such variations and modifications as properly fall within the scope of my invention and the terms of the following claims.

What I claim is:

1. A flange lubricator comprising, in combination, a casing, a lubricant supply receptacle communicating with said casing, a

hollow plunger mounted for reciprocation in said casing, a lubricant brush projecting from the outer end of said hollow plunger, a sleeve surrounding said brush, said sleeve and brush arranged to contact with a wheel flange and adapted to reciprocate said plunger upon lateral movement of said flange whereby to force oil or other lubricant from said casing along the bristles of said brush. 75

2. A flange lubricator comprising, in combination, a hollow casing communicating at one end with a source of lubricant supply, a lubricant brush projecting through the opposite end of said casing adapted to contact with a wheel flange, a plunger in said casing having an opening communicating with the inner end of said brush and arranged to be reciprocated by lateral movement of the wheel flange and means to maintain said brush in engagement with the flange. 85

3. A flange lubricator comprising, in combination, a tubular casing, a lubricant receptacle connected to said casing, a reciprocable brush projecting from one end of said casing and adapted to engage a wheel flange, a plunger in said casing arranged to reciprocate with said brush, and having a tubular rearward extension of less diameter 90 than the diameter of said casing, guiding means for said tubular extension, said extension presenting a slot to permit lubricant to flow therein from the interior annular space in said casing and means to maintain the brush in engagement with the flange. 100

4. A flange lubricator comprising, in combination, a substantially horizontal tubular casing having a lubricating brush projecting from one end and arranged to contact with a wheel flange, a lubricant receptacle above the opposite end of said casing and communicating therewith through one side, a tubular plunger reciprocatable within said casing and presenting a plurality of slots to permit lubricant to flow therethrough into the inner end of the brush, said plunger arranged to be reciprocated by the lateral motion of the wheel flange. 105

5. A flange lubricator comprising, in combination, a substantially horizontal casing presenting a reciprocable lubricator brush projecting through one end thereof, a lubricant receptacle above said casing and connected therewith near the opposite end, a tubular plunger reciprocable within the casing for supplying lubricant to said brush, said tubular plunger communicating with the interior of said casing, a spring operatively interposed between one end of said casing and said tubular plunger whereby to maintain the plunger in its outermost position with the brush engaging the wheel flange, and means associated with said brush adapted to reciprocate said plunger to feed 115 120 125 130

the lubricant through the bristles of said brush to the flange.

6. In a flange lubricator for wheels, an oil container, a casing communicating with said oil container, a slidable hollow plunger mounted in said casing provided with slots, a sleeve attached to said plunger and provided with a brush and means for causing said plunger to be moved inward and forcing the oil lengthwise through the bristles of the brush to the flange of a wheel.

7. In a flange lubricator for wheels, an oil container, a casing communicating with said oil container, a barrel having a pin, a plunger, slidable in said barrel and casing, provided with a plurality of longitudinal slots through which said pin extends, a head forming a tight joint with the interior wall of said casing, a sleeve carrying a brush mounted on the inner end of said plunger and spring means normally urging said plunger and brush outwardly so that the brush will engage the flange of a wheel, said plunger and brush arranged to be forced inwardly of the sleeve by the flange.

8. In a flange lubricator for wheels, an oil container, a casing, a pipe connecting said oil container and casing, a series of inlet openings in said casing forming a communication between said pipe and casing, a stationary barrel secured in the outer end of said casing having a chamber therein containing a spring and a pin, a plunger slidably mounted in the chamber of said barrel provided with slots through which the pin of the barrel passes and a head slidable in the said casing provided with a projection, a brush secured to said projection, a sleeve slidable in the inner end of said casing and enclosing said brush and means for connecting said sleeve and brush to the plunger, said sleeve and brush being normally urged outwardly into engagement with the flange of a wheel by said spring and adapted to be forced inwardly by the flange to pump oil through the bristles of the brush to the flange.

In testimony whereof I have affixed my signature.

LOUIS N. VINCENT.
